VACUUM CLEANER

Charles Lyman Brown, Jr., Old Greenwich, Conn.,
assignor to Electrolux Corporation, Dover, Del.,
a corporation of Delaware

Application December 19, 1935, Serial No. 55,179

14 Claims.

(Cl. 248—2)

My invention relates to vacuum cleaners and more particularly to an improved means for supporting a motor or motor-fan unit within the casing of a vacuum cleaner.

One of the objects of my invention is to provide a supporting means which admits of ready insertion and removal of the motor unit from the casing without requiring the tightening or loosening of bolts or the like. Another object of my invention is to provide a support having the above characteristics and also providing a certain degree of resiliency in the mounting.

Further objects and advantages of my invention will be apparent from the following description considered in connection with the accompanying drawing which forms a part of this specification and of which:

Fig. 1 is a cross-sectional view of a vacuum cleaner embodying my invention;

Fig. 2 is a cross-sectional view taken on the line 2—2 of Fig. 1;

Fig. 3 is a view on a somewhat larger scale showing a portion of the device illustrated in Fig. 2;

Fig. 4 is an elevational view of the structure shown in Fig. 3; and

Fig. 5 is a cross-sectional view taken on the line 5—5 of Fig. 3.

Referring more particularly to Fig. 1, reference character 10 designates generally a casing which may comprise an upper stamping 12 and a lower stamping 14 suitably joined together, as by welding, along the seam 16. The interior of casing 10 is divided into a dust bag compartment 22, a motor compartment 24, and a discharge compartment 26, by partitions 18 and 20.

The end of casing 10 bounding compartment 22 is formed with a dust bag opening 28, which may be closed by means of a cover 30 secured to the main part of the casing by any suitable means. Cover 30 is provided with a threaded opening 32 adapted to receive one end of a flexible hose 34. The other end of the hose may be attached to a rigid tubular member 36 having a cleaning implement, such as a suction nozzle 38, secured to the other end thereof. A dust bag ring 40 is provided with a flange 42 adapted to be clamped in place in opening 28 by means of cover member 30. A dust bag 44 of cloth or other material pervious with respect to air but impervious with respect to dust is secured to ring 40. The closed end of bag 44 presses against a plate 46 resiliently mounted on a perforated plate 50 which is fastened to partition 18 and serves as a guard for an opening 52 in the partition.

The stamping 14 is formed with an opening 54 in alignment with motor compartment 24, which opening may be closed by means of a cover plate 56 removably secured in place by means of bolts 58. Opening 54 is sufficiently large so that a motor-fan unit, generally designated by reference character 59, may be inserted and removed therethrough. This unit includes spaced rings 60 and 62 joined by means of a cylindrical case 64. Supported from the rings and within the case by means of a plurality of conical springs 66 is an electric motor 68 having a shaft 70, upon which are mounted fan rotors 72. These rotors are enclosed within a fan housing 74 suitably secured to ring 62.

Motor-fan unit 60 is supported within chamber 24 by means of abutments 76 and expandable and contractible structures 78. The abutments may consist of rubber pieces suitably secured to the motor-fan unit and receivable within depressions 80 formed in the top of the upper stamping 12. While these abutments have a certain amount of resiliency, they are substantially non-deformable. Structure 78 includes a hollow cylinder 82 pivotally secured, by means of a pin 84, to a bracket 86 secured to the interior of lower stamping 14. Reciprocably mounted within cylinder 82 is a cylinder or pin 88 which may be made of molded rubber or "bakelite" and is urged outwardly by means of a spring 90 confined between the end of the pin and the closed bottom 92 of the cylinder. Opposite walls of the cylinder may be flanged inwardly, as shown at 94 so as to engage shoulders 96 formed on the pin to limit outward movement of the latter. Rings 60 and 62 are formed with recesses 98 which are adapted to receive the outer ends of pins 88 when the motor-fan unit is mounted in position within chamber 24. As shown, an abutment 76 and a pair of structures 78 are disposed around the unit in alignment with each of rings 60 and 62. Hence two three-point suspensions are provided for the unit adjacent either end of the motor 68, which is by far the heaviest part of the unit. If desired, a single three-point suspension could be located in a plane passing through the center of gravity of the unit.

The forward wall of fan housing 74 is formed with an inlet opening surrounded by a flange 100 and opening 52 in partition 18 is provided with a similar flange 102. A short section of flexible tubing 104 may be secured to flanges 100 and 102 for providing an air-tight connection between partition 18 and fan housing. Ring 60 and partition 20 are formed with similar flanges

which may be connected by means of flexible tubing 106, thus providing an air-tight connection between the ring and the partition.

The end wall of casing 10 bounding exhaust chamber 26 is provided with a threaded outlet opening 108 to which the hose 34 may be attached when it is desired to use the vacuum cleaner for blowing. The bottom stamping 14 is formed with ridges 110 which serve to support the cleaner on a surface, while the handle 112 is provided for carrying the cleaner.

The motor-fan unit 59 may be inserted in the following manner:

Cover plate 86 being removed, the motor-fan unit may be inserted through opening 54, the structures 78 being pivoted to the position shown in dot and dash lines in Fig. 2. The tubings 104 and 106 may be secured either to the flanges on the partitions or to the flanges formed on the motor-fan unit before the latter is inserted and, due to the flexibility of the tubing, the unit may be inserted and the tubing then placed over the cooperating flanges. When the unit is thus in place, the members 78 may be pivoted to the positions shown in Fig. 2 by forcing the pins 88 into the cylinders 82 and then releasing the pins, whereby they will engage within the recesses 98 formed in rings 80 and 82. The springs 86 are of sufficient strength to force the motor-fan unit 30 upwardly against the abutments 76 which latter are thus pressed into contact with the recesses 88 in the casing. Brackets 86 are formed with stops 114 which limit pivotal movement of the cylinders 78 so that the weight of the motor-fan 35 unit cannot pivot the cylinders beyond the position shown in Fig. 2. The center lines of the pins 88 and cylinder 78 pass below the center of gravity of the motor unit, whereby the weight of the unit has no tendency to pivot the cylinders 40 in the opposite direction.

Due to the fact that abutments 76 and pins 78 are received in recesses, axial displacement of the unit is prevented. As a matter of fact, abutments 76 alone are sufficient to prevent such 45 movement and thus relieve the structure 78 of strain.

In order to remove the motor-fan unit, it is only necessary to retract the pins 88 into the cylinder 78 far enough so that the pins are released from the recesses 98, whereupon the cylinders and pins may be pivoted to the position shown in dot and dash lines in Fig. 2.

In operation the rotation of the fan rotors by the electric motor causes air to be drawn 55 in through nozzle 38 tubular member 36 and hose 34 to the interior of the dust bag. Any dust carried along by this air is deposited within the dust bag, while the air passes through the material of the bag, and through tubing 104 to the 60 fan. From the fan, the air is discharged through and around the motor and through tubing 106 to compartment 26, from which it escapes to the atmosphere through outlet 108. Rotation of the motor and fan sets up vibration which, if not 65 damped, would result in an excessive amount of noise. Much of this vibration is absorbed by the springs 86, while most of the remainder is prevented from reaching the casing 10 by means of the rubber abutments 76 and the springs 88 70 in the supporting structure 78.

Thus it will be seen that the means provided for supporting the motor-fan unit not only permits ready insertion and removal of the unit but also aids in the absorption of vibration produced 75 by the operation of the motor.

While I have shown and described one more or less specific embodiment of my invention it is to be understood that modifications thereof fall within its scope, which is to be limited only by the appended claims viewed in the light of the prior art.

What I claim is:

1. In a vacuum cleaner, a casing member, a motor member, and means for removably mounting said motor member in said casing member including resiliently expandable and contractable structure pivotally connected to one of said members and pivotable into and out of engagement with the other of said members.

2. In a vacuum cleaner, a casing member, a motor member, and means for removably mounting said motor member in said casing member including resiliently expandable and contractable structure pivotally connected to one of said members and pivotable into engagement with the other of said members, said structure and the other of said members being formed with a co-operating recess and projection for preventing pivoting of said structure while in expanded state.

3. In a vacuum cleaner, a casing member, a motor member, and means for removably mounting said motor member in said casing member including resiliently expandable and contractable structure pivotally connected to said casing member and pivotable into and out of engagement with a recess formed in said motor member.

4. In a vacuum cleaner, a casing member, a motor member, and means for removably mounting said motor member in said casing member including an abutment between said members and resiliently expandable and contractable structure pivotally connected to one of said members and pivotable into engagement with the other of said members for holding said members 40 in contact with said abutment.

5. In a vacuum cleaner, a casing member, a motor member, and means for removably mounting said motor member in said casing member including an abutment between said members and resiliently expandable and contractable structure pivotally connected to one of said members and pivotable into engagement with the other of said members for holding said members in contact with said abutment, said abutment being received in recesses formed in said members whereby displacement of one of said members parallel to the others is prevented.

6. In a vacuum cleaner, a casing, a motor unit, and means for removably mounting said unit in said casing including a first member pivotably connected to said casing and a second member resiliently carried by said first member, said members being pivotable into and out of engagement with said unit.

7. In a vacuum cleaner, a casing, a motor unit, and means for removably mounting said unit in said casing including substantially non-deformable means between said unit and said casing and resiliently deformable means pivotally connected to said casing and pivotable into engagement with said unit for holding said unit in contact with said non-deformable means.

8. In a vacuum cleaner, a casing, a motor unit, and means for removably mounting said unit in said casing including a hollow member pivotably secured to said casing, a pin reciprocably mounted in said member, and a spring within said member urging said pin outwardly into engagement with said unit.

9. In a vacuum cleaner, a casing, a motor-unit, and means for removably mounting said unit in said casing including an abutment between said casing and said unit, a hollow member pivotally secured to said casing, a pin reciprocally mounted in said member, and a spring within said member urging said pin outwardly into engagement with said unit, thereby pressing said unit against said abutment.
- 10 10. In a vacuum cleaner, a casing, a motor unit, and means for removably mounting said unit in a horizontal position in said casing including an abutment between said casing and the upper part of said unit and a pair of resiliently expandible and contractable structures pivotally connected to said casing and disposed symmetrically around the periphery of said motor unit with respect to said abutment, said structure being pivotable into engagement with the lower part of said motor unit, and means for limiting pivotal movement of said structures towards the bottom of said unit, said last mentioned means being so positioned that when said structures are in contact therewith, the center lines of said structures pass below the center of gravity of said unit.
- 11 11. In a vacuum cleaner, a casing, a motor unit, and means for removably mounting said unit in said casing including an abutment between said unit and said casing, a plurality of hollow members pivotally secured to said casing, a pin reciprocably mounted in each member, and a spring within each member urging said pin outwardly into engagement with said unit.
- 12 12. In a vacuum cleaner, a casing including a substantially flat bottom wall, means defining a motor compartment within said casing, said bottom wall being formed with an opening communicating with said motor compartment, a motor unit adapted to be inserted through said opening, and means for mounting said unit within said compartment including resiliently expandible and contractable structure pivotally secured to said casing adjacent to said opening, said structure being pivotable out of the path traversed by said unit for insertion of the latter into said compartment and being pivotable into engagement with said unit after the latter has been inserted to press said unit against said abutment.
13. In a vacuum cleaner, a casing including a substantially flat bottom wall, means defining a motor compartment within said casing, said bottom wall being formed with an opening communicating with said motor compartment, a motor unit adapted to be inserted through said opening, and means for mounting said unit within said compartment including resiliently expandible and contractable structure pivotally secured to said casing adjacent to said opening, said structure being pivotable out of the path traversed by said unit for insertion of the latter into said compartment and being pivotable into engagement with said unit after the latter has been inserted.
14. In a vacuum cleaner, a casing including a substantially flat bottom wall, means defining a motor compartment within said casing, said bottom wall being formed with an opening communicating with said compartment, a motor unit adapted to be inserted through said opening, and means for mounting said unit within said compartment including an abutment between the upper part of said unit and said casing and resiliently expandible and contractable structure pivotally secured to said casing adjacent to said opening, said structure being pivotable out of the path traversed by said unit for insertion of the latter into said compartment and being pivotable into engagement with said unit after the latter has been inserted to press said unit against said abutment.

CHARLES LYMAN BROWN, JR.
